WILLIAM DICKS, OF DUMBARTON, SCOTLAND.

TREATMENT OR PRODUCTION OF SEAMLESS METAL TUBES OR BILLETS.

1,177,397. Specification of Letters Patent. Patented Mar. 28, 1916.

Application filed December 27, 1910. Serial No. 599,471.

To all whom it may concern:

Be it known that I, WILLIAM DICKS, a subject of the King of Great Britain, residing at Dumbarton, Scotland, have invented certain new and useful Improvements in the Treatment or Production of Seamless Metal Tubes or Billets, of which the following is a specification.

This invention relates to the treatment or production of seamless metal tubes, from solid billets or from hollow billets, and also to the treatment or production of rods from billets.

The invention refers to that class of apparatus wherein the working surfaces of disks, rolls or the like which act upon the billet or work are provided with one or more series of spirally arranged grooves and ridges which act upon the surface metal of the workpiece and feed it or move it relatively to the remaining portion of the metal of the workpiece. Hitherto such disks or rolls of such mills have been located to form a pass converging in the direction of travel of the workpiece, and these mills have been used for the production, or reduction of a tube from a hollow billet, by reducing the thickness of the walls of the workpiece, with or without a reduction in the diameter of the workpiece and the spiral grooves and ridges have acted to feed back or retard the flow of the surface metal of the workpiece. Now according to the present invention, the reducing or acting surfaces, each comprising grooves and ridges such as described in the said specification, are so disposed on the working faces forming the walls of a diverging pass that when the rolling device rotates they act to accelerate the feed or flow of the outer or surface metal of the portion of the workpiece under treatment, or the ridges and grooves upon one part of the working surface of the rolling devices forming the walls of a converging part of the pass are disposed so as to retard the feed and the ridges and grooves on the faces forming the walls of a diverging part of the pass are disposed so as to accelerate the feed of the surface metal, also ridges and grooves which retard the flow or feed back the metal are employed as hereinafter described. The disposition and direction of rotation of the rolling devices depend upon, the class of mill and the operation to be effected, as does the angle or disposition of the working face of the rolling device with re-

lation to the axis of rotation, and the construction and disposition of the piercing or supporting mandrel. The ridges and grooves may be so arranged as to act upon the workpiece either when it first enters the pass or when it has traveled beyond the axis of the rolling device. All the ridges or grooves have their initial points situated on a circle concentric with the axis of rotation of the rolling device and this circle may be the edge of the working face of the rolling device or the edge of a flat or finishing part. Similarly all the ridges and grooves terminate in another circle concentric with the axis of the disk, the circle being the edge of the working face, the edge of a finishing surface, or a circle forming the initial points of a second working face also formed of series of ridges and grooves as hereinafter described. The grooves and ridges are so arranged and proportioned that in their action upon the workpiece they act either by the convex or by the concave surfaces. They are disposed eccentrically or spirally around the working surfaces of the rolling devices, their action upon the workpiece being more a stretching action in a longitudinal direction than a process of reducing by circumferential rolling. In all cases whether the ridges and grooves are arranged to accelerate or feed forward, retard, or accelerate and retard or feed back the surface metal, the arrangement and effect are such that the metal is not crowded into the pass between the rolling devices, tending thereby to upset the workpiece; but is, according to the present invention, caused to flow evenly and smoothly and all the grooves and ridges act successively on the portion of the workpiece under treatment so that a tube with walls of, or a rod of, uniform thickness, and untwisted fibers is produced and the workpiece is under complete control throughout its passage through the mill.

Referring to the accompanying drawings:—Figure 1 is a sectional plan on the line 1—1 of Fig. 3 of an apparatus or mill comprising two opposed rotary rolling devices, in the form of disks, each provided with two series of grooves and ridges according to the present invention the working faces of the disks being so formed that one pair of the opposed faces or parts on the two disks form the walls of a converging pass and the other pair form a diverging

pass, the ridges and grooves on the walls of the converging part of the pass being adapted when the disks rotate to retard the flow of the metal and those on the walls of the diverging part being adapted to accelerate the flow of the said metal. Fig. 2 is a face view of one of the disks shown in Fig. 1. Fig. 3 is an end elevation of the mill shown in Fig. 1. Fig. 4 is a face view of a disk having two series of ridges and grooves similar to Figs. 1 and 2 but arranged for the billet or workpiece to enter the opposite end of the pass. Fig. 5 is face view of a disk having one series of ridges and grooves arranged to accelerate the flow of the surface metal and the working face on which these are formed arranged to form a converging pass. Fig. 6 is a sectional plan of Fig. 5. Fig. 7 is a face view of a disk similar to Fig. 5 but with the grooves and ridges arranged on a working face of the disk at the opposite end of the pass to those of Fig. 5. Figs. 8 and 9 are front elevation and plan respectively showing a modified arrangement of the relative positions of the disks. Figs. 10, 11 and 12 are respectively side elevation, end elevation, and plan, showing an embodiment of the invention applied to rolls. Fig. 13 is a horizontal sectional view on an enlarged scale, of a portion of the disk shown in Figs. 5 and 6.

The same letters of reference are employed throughout the drawings to denote the same or similar parts or features.

35 A and A¹ are the rotary rolling devices, A² are the retarding ridges and grooves and A³ are the accelerating ridges and grooves; B the piercing or other mandrel and C is the billet, or workpiece.

40 Referring first of all to the arrangement shown in Figs. 1 to 3 which illustrate an embodiment of the invention for piercing a solid billet and subsequently reducing the walls of the pierced billet to form a tube, 45 according to this embodiment the disks A A¹ are provided with two adjoining working or acting surfaces α α^1 and the arrangement and disposition are such that the workpiece is engaged by these surfaces successively 50 after it has passed beyond the center or axis of rotation of the disks. The first pair of opposed surfaces α form the opposite walls of the converging part of the pass and are each provided with grooves and ridges A² 55 which retard or feed back the surface metal of the part of the billet C engaged by them and the second or outer pair of opposed surfaces α^1 which form the opposite walls of the diverging part of the pass are each provided with ridges and grooves A³ which accelerate the flow of the said metal. The grooves and ridges of the first series A² are disposed in spiral form over the working face of the disk forming the wall of the converging part of the pass and this series ex-

tends as shown in Figs. 1 and 2 from a circle α^3 forming the initial edge of the working surface to a more or less imaginary circle α^4 at the junction of the two working surfaces. The grooves and ridges of the second series A³ which are arranged in similar form to those of the first series extend from the circle α^4 to the outer edge α^5 of the working surface α^1 . Each groove and ridge of the series A³ has its initial point at or about the terminal point of a groove and ridge of the series A². The piercing mandrel B which, when the billet after piercing is reduced, is conveniently carried by a mandrel B¹ supporting the billet while being reduced, is situated so that the point thereof is at or about the junction of the two working surfaces or at or about the junction of the converging and diverging parts of the pass and the billet is supported by guides E E¹, such as are commonly employed for supporting and guiding a billet. By the system of grooves and ridges which I propose using, this circumferential rolling is changed to a rolling process whereby a stretching action is effected in the longitudinal direction of the workpiece, and thereby the diameter of the ingot is reduced in such a manner that no subsequent expansion takes place after the material has passed over the piercing point. By this arrangement the metal is gently coaxed over the piercing point since the grooves and ridges pass over the same part of the billet a number of times. Further, twist of the fibers is minimized or eliminated, overcrowding of the metal into the pass is avoided, therefore undesired expanding or enlarging of the diameter of the tube is prevented, and no bursting of the walls can take place. As the workpiece enters the pass into which it is drawn by the initial gripping surfaces, each being a narrow flat face α^6 turned on the disks, working parallel or nearly so, with the axis of the billet, the grooves and ridges attack the workpiece in such a manner that there is formed on the outer surface thereof a succession of screw-like formations and as the workpiece continues to advance into the pass with the known helical motion, the pitch of the screw or thread-like formations formed on the outer surface of the workpiece is continuously varied and the depth of the screw or thread is simultaneously decreased till the end of the bite is reached where the screw or thread formations disappear. During the formation of the screw or thread on the outer surface of the billet by the back cam like action of the ridges and grooves the outer surface of the billet to a depth about equal to the depth of groove is retarded in its passage in relation to the body of the billet and by this means overcrowding at the end of the bite is prevented. When the material of the billet has advanced as far as

the end of the bite it encounters the piercing point and at this point it is advantageous to accelerate the passage of the now hollow billet through the pass to prevent expansion 5 of the material and bursting of the walls of the billet where a flaw in the metal appears; this acceleration of the passage of the material is accomplished by the grooves and ridges on the outlet or rounding up side of 10 the bite in such a manner that the grooves and ridges form with those on the inlet side a wedge whose action on the workpiece is such as to push back or retard the flow of the surface metal on the bite side and to 15 push forward the surface metal on the outlet or rounding up face and thus a double stretching action is obtained, and a considerable reduction of the pressure on the piercing point. Each groove and ridge may be 20 carried around the surface of the disk once or more. Between the outer edge of the second or accelerating series of ridges and grooves A³ and the outer edge of the disk is situated 25 a finishing or smoothing surface a⁷ which can be parallel or nearly so with the axis of the billet and at the inlet end of the pass there are provided conveniently, similar initial gripping surfaces a⁶. The disks A and A¹ rotate in opposite directions and the 30 initial feed is imparted to the billet or workpiece C by the known method of arranging the disks so that their axes are situated in different planes as shown in Fig. 3.

The arrangement shown in Figs. 1 to 3, in 35 addition to being employed as described for producing a tube of required dimensions in one operation, may also be employed for producing a hollow billet from a solid one. It can also be used for expanding the 40 diameter of tubes, and reducing the thickness of the walls of tubes or pierced billets.

Instead of arranging the working surfaces and disposing the disks so that the billet is first engaged at the inner side of 45 the pass as in the arrangement according to Figs. 1 to 3, these may be so arranged and disposed that the billet is engaged at the outer edges of the disks or end of the pass as shown in Fig. 4. In this case the surface 50 a having the retarding ridges and grooves A² is situated at the outer edge of the disk and the surface a¹ having the accelerating grooves and ridges A³ between a and the center of the disk. The surfaces are arranged however as in the previous example 55 so that the grooves and ridges for retarding are on the surfaces forming the walls of the converging part of the pass and the accelerating grooves and ridges on the surface forming the walls of the diverging part 60 of the pass.

The grooves and ridges for retarding the flow of the surface metal as shown in Figs. 1 to 3 may be dispensed with, the walls of 65 the converging part of the pass being left

smooth. A disk having such an arrangement of its members is illustrated in Figs. 5 and 6. Similarly with the arrangement shown at Fig. 4, where the accelerating grooves and ridges are at the inner side of 70 the working surfaces, the retarding grooves and ridges at the outer side of the disks may be dispensed with, the walls of the converging part of the pass being left smooth as shown in Fig. 7. 75

The arrangements shown in Fig. 4 and in Figs. 5 and 6 may be employed for the same purposes as stated with regard to the arrangements in Figs. 1 to 3.

The modification shown in Figs. 8 and 9 80 refers to the disposition of the disks only to obtain the feed of the billet as a whole, as disks having working surfaces according to any of the above described arrangements may be employed, the pass having 85 converging and diverging parts as already described. As shown in these two figures, the axes of both disks are situated in the same horizontal plane and the longitudinal axes of the billet and mandrel are disposed 90 below the axes of both disks. This arrangement can be employed for any of the purposes described with reference to the previously described arrangements.

The arrangement or disposition of the 95 disks themselves is independent of the ridges and grooves forming the essential feature of the present invention. When forming these grooves and ridges the purpose for which the disk are to be employed and the manner in which they are to be disposed must 100 be considered and in all cases the grooves and ridges, as already stated, are so arranged that where the disks present for the traverse of the workpiece a converging pass the grooves and ridges retard the flow of or feed back the surface metal and where the pass presented is a diverging one the grooves and ridges hasten or accelerate the flow, the 105 action in all cases being gradual and evenly distributed due to the fact that a number of grooves and ridges act in succession upon the portion of the workpiece under treatment.

In place of disks, cylindrical rolling devices or rolls may be employed as shown in Figs. 10 to 12 with retarding ridges and grooves on the surfaces forming the walls of the converging part of the pass, and accelerating grooves and ridges on the diverging part thereof. The one series of grooves and ridges is adapted and arranged to give a backward feed or a retarding action to the surface metal, where the pass converges, and the grooves and ridges upon the diverging part produce an accelerating action. When using rolls the retarding series of grooves and ridges may be omitted or replaced, as above stated, by a plain or smooth surface oppositely inclined or arranged to 115 120 125 130

provide a feeding action to the workpiece. As shown in Fig. 11 the work piece may as is customary be supported by guides E. Where rolls such as described are employed they may be employed for any of the purposes as already described with reference to Figs. 1 to 3.

The grooves and ridges each vary in depth throughout their entire length or they 10 may vary in pitch, or they may vary both in pitch and depth. Preferably the grooves and ridges are shallow at their initial and final ends, as shown in Fig. 13, the deepest part being in the middle of their length but 15 this may be varied according to requirements.

Having now described my invention what I claim and desire to secure by Letters Patent is:—

20. 1. In an apparatus or mill for the treatment or production of seamless metal tubes or billets the combination of opposed rotary rolling devices having working surfaces forming a pass which converges at the initial 25 or entrance end and diverges at the exit end, whereby the workpiece is fed into and through the pass, the portions of said working surfaces forming the converging part of the pass being adapted to act continuously 30 on the part of a workpiece under treatment and to force back the surface metal of said part in opposition to the normal feed of the workpieces and the portions of said working surfaces forming the diverging 35 part of the pass being adapted for feeding forward or accelerating the flow of the surface metal of the part of the workpiece under treatment relatively to the normal feed of the workpiece.
40. 2. In an apparatus or mill for the treatment or production of seamless metal tubes or billets the combination of opposed rotary rolling devices having working surfaces forming a pass which converges from its 45 inlet or initial end and diverges toward the outlet or exit end, a mandrel situated in the pass, means on the working surfaces of the devices forming the walls of the converging part of the pass adapted to act on the surface metal of a workpiece to retard the flow of or feed back said surface metal in opposition to the normal feed of the workpiece, and means on the working surfaces of the devices forming the walls of the diverging 50 portion of the pass adapted to accelerate the forward flow of the surface metal of the workpiece relatively to the normal feed of the workpiece.
55. 3. In an apparatus or mill for the treatment or production of a seamless metal tube or billet, the combination of opposed rotary rolling devices having working surfaces forming a pass which first converges and then diverges, a mandrel located in the pass, means on the working surfaces of the de-

vices forming the walls of the converging portion of the pass adapted to retard or feed back the surface metal of the workpiece in opposition to the bodily feed of the workpiece, means on the surfaces of the devices forming the walls of the diverging part of the pass adapted to accelerate the flow of the surface metal of the workpiece relatively to the bodily feed of the workpiece under the normal feeding means, and initial gripping surfaces on the rotary rolling devices.

4. In an apparatus or mill for the treatment or production of a seamless metal tube or billet, the combination of opposed rotary rolling devices, furnished with working surfaces and located to form a diverging pass for the workpiece, and means on the working surfaces of the devices for accelerating the forward flow of the surface metal 85 of a workpiece relatively to the bodily feed of the workpiece.

5. In an apparatus or mill for the treatment or production of a seamless metal tube or billet, the combination of opposed rotary rolling devices, furnished with working surfaces and arranged and located to form a pass which first converges and then diverges, and means on the surfaces of the devices forming the diverging part of the pass 95 adapted to act upon a workpiece and accelerate the forward flow of the surface metal thereof relatively to the bodily feed of the workpiece.

6. In an apparatus or mill for the production or treatment of a seamless metal tube, the combination of opposed rotary rolling devices, having working surfaces forming a pass which first converges from the inlet toward the outlet end and then diverges toward the exit, a plurality of ridges and grooves arranged spirally on the surfaces of the devices forming the converging part of the pass to act on a workpiece and feed back or retard the flow of the surface metal thereof 110 in opposition to the bodily feed of the workpiece, and a plurality of spiral ridges and grooves on the surfaces of the devices forming the diverging portion of the pass arranged to act on the workpiece and accelerate the flow of the surface metal thereof 115 relatively to the bodily feed of the workpiece.

7. In an apparatus or mill for the treatment or production of a seamless metal tube, the combination of opposed rotary rolling devices, having working surfaces forming a pass which first converges from the inlet toward the outlet end and then diverges toward the exit, a plurality of spirally arranged 125 ridges and grooves on the surfaces of the devices forming the walls of the converging part of the pass adapted to feed back or retard the flow of the surface metal of a workpiece in opposition to the bodily feed 130

- thereof, a plurality of spirally arranged ridges and grooves on the surfaces of the rolling devices forming the walls of the diverging portion of the pass adapted to act 55 on the workpiece to accelerate the flow of or feed forward the surface metal thereof relatively to the bodily feed of the workpiece, and a mandrel located in the pass between the rolling devices.
- 10 8. In an apparatus or mill for the treatment or production of a seamless metal tube or billet, the combination of opposed rotary rolling devices having working surfaces forming a pass for a workpiece which 15 first converges and then diverges, a mandrel located in the pass between the rolling devices, a plurality of spirally arranged grooves and ridges on the surfaces of the devices forming the walls of the converging 20 part of the pass adapted to retard or feed backward the surface metal of a workpiece in opposition to the bodily feed thereof, a plurality of spirally disposed grooves and ridges disposed on the surfaces of the rolling 25 devices forming the walls of the diverging part of the pass and adapted to accelerate the flow of the surface metal relatively to the bodily forward feed of the workpiece, and initial gripping surfaces on the rolling 30 devices.
9. In an apparatus or mill for the treatment or manufacture of a weldless tube or billet, the combination with opposed rotary rolling devices furnished with working surfaces arranged and located to form a diverging 35 pass, for a workpiece, a mandrel located in the pass, and a plurality of spirally arranged grooves and ridges on the working surfaces of the rolling devices for accelerating the forward feed of the surface metal of the workpiece relatively to the bodily forward feed of the workpiece.
10. In an apparatus or mill for the treatment or manufacture of a seamless metal tube or billet, the combination of opposed rotary rolling devices furnished with working surfaces arranged and located to form 45 a pass which first converges and then diverges, a mandrel located in the pass between the rolling devices, and a plurality of spirally arranged grooves and ridges on the surfaces of the rolling devices forming the walls of the diverging part of the pass adapted to act on a workpiece and accelerate the flow or feed forward the surface metal thereof relatively to the bodily feed of the workpiece.
11. In an apparatus or mill for the treatment or manufacture of a seamless metal tube or billet, the combination with opposed rotary rolling devices having working surfaces arranged and located to form a pass which first converges and then diverges, of a plurality of retarding ridges and grooves arranged spirally on the surfaces of the devices forming the converging part of the pass, a plurality of accelerating ridges and grooves arranged spirally on the surfaces of the devices forming the diverging part of the pass, and a mandrel located in the pass between the rolling devices.
12. In an apparatus or mill for the treatment or manufacture of a seamless metal tube or a billet, the combination with opposed rotary rolling devices having working surfaces arranged and located to form a diverging pass, of a plurality of accelerating ridges and grooves arranged spirally on the working surfaces, and a mandrel located in the pass between the rolling devices.
13. In an apparatus or mill for the treatment or manufacture of a seamless metal tube or a billet, the combination with opposed rotary rolling devices, of a plurality of spirally arranged grooves and ridges on one part of each rolling device adapted to retard the flow of the surface metal of a workpiece in opposition to the normal feed thereof, and a plurality of spirally arranged ridges and grooves on another portion of the working surfaces adapted to accelerate the flow or feed forward the surface metal or the workpiece relatively to the normal feed thereof, and a mandrel located in the pass between the rolling devices.
- In testimony whereof I have signed my name to this specification in the presence of two subscribing witnesses.
- WILLIAM DICKS.
